Patent and Trademark Office, Washington, D. C.: To all whom it may concern: Be it known that I, VINCENZO PETRUCCIONE, a citizen of the Kingdom of Italy, residing at Amsterdam, in the Netherlands, have invented a new and useful improvement in a loom, which improvement is described in the following specification, and is illustrated in the accompanying drawings.

UNITED STATES PATENT OFFICE

2,351,364

LOOM

Vincenzo Petruccione, Amsterdam, N. Y.

Application December 10, 1943, Serial No. 513,672

9 Claims. (Cl. 139—123)

This invention relates to weft inserting mechanisms or needle motions for use on looms, such as those of the Axminster type, in which the weft thread is carried through the shed by a needle and interlocked with a selvage cord passed through it by a shuttle, after which the inserted shot of weft is beaten up by a lay. More particularly, the invention is concerned with a novel needle motion of the type referred to, which is superior to and offers numerous advantages over prior similar mechanisms in that it is of simpler construction, so that it is less expensive to build and easier to keep in working order, and it imparts to the needle a motion which is more nearly uniform with respect to both length of travel and speed. The new mechanism may be readily adjusted to vary the length of the path of travel of the needle and also to vary the speed at which the needle moves and it may be installed without difficulty in existing looms as well as applied to new looms.

In Axminster looms as now commonly constructed, the needle is attached to a carriage movable along a rail at one side of the loom and the carriage is secured to a rope, which is led around a pair of pulleys at opposite ends of the rail and has its ends wound oppositely about and attached to a drum. The drum is mounted on an axle provided with a pinion, and by a suitable gear, such as a segment gear, meshing with the pinion and rocked by a crank on a shaft, the drum is rotated first in one direction and then in the other. During such movement of the drum, the rope is moved back and forth along the rail and reciprocates the needle carriage connected to it and the needle mounted in the carriage. Such a needle motion is quite complex, because it includes a number of gears, shafts, pulleys, etc. and it is both costly to build and expensive to keep in repair. The needle motion described is subject to the further objection that, because of slack or stretching of the rope or for other reasons, the needle does not always come to rest smoothly and in proper relation to the selvage shuttle, and this causes trouble in the interlocking of the selvage cord with the inserted weft shot.

The present invention is directed to the provision of a needle motion which overcomes the disadvantages of the prior needle motions and is simpler in construction and superior in performance. In the new motion, the needle is attached to a carriage movable along a rail and connected to a lever which is part of a lazy-tongs system of levers and lies at one end of the

system. At the other end of the system, means are provided for extending and retracting the system and thereby moving the needle carriage back and forth along the rail and inserting the needle into and withdrawing it from the shed. The mechanism also includes means limiting the travel of the needle in both directions and means for taking up slack in the system so that the needle comes smoothly to rest at opposite ends of a definite path of travel without overrunning.

For a better understanding of the invention, reference may be made to the accompanying drawings, in which

Fig. 1 is a view in side elevation of the new needle motion showing the parts in the positions that they occupy when the needle is in retracted position;

Fig. 2 is a view similar Fig. 1 showing the parts in the positions that they occupy when the needle is in advanced position;

Fig. 3 is a sectional view on the line 3—3 of Fig. 1;

Fig. 4 is a sectional view on the line 4—4 of Fig. 2; and

Fig. 5 is a view in side elevation of a modification.

The needle motion in the form illustrated in Fig. 1 includes a rail 10 provided with a metal facing strip 11 and mounted on uprights 12 at one side of the loom, the rail lying at right angles to the direction of the warp threads. A carriage is movable along the rail and it includes a plate 13 mounted on a shaft 14 which serves as the axle of a roller 15 movable along the strip 11 and of another roller 16, which runs between upper and lower angle bars 17, 18 attached to brackets 19 connected to a rail 20 supported on the uprights 12 above rail 10. The rail 10 is formed with a longitudinal slot 21 into which a part of plate 13 extends and a needle 22 lies within the slot and is connected at one end to the portion of the plate within the slot.

The needle carriage is connected to one end 45 of a lever 23, which is an element of a lazy-tongs system of levers and lies at one end of the system. The other end of lever 23 is connected to one end of a lever 24 and the midpoint of lever 23 is connected to one end of a lever 25, the other end of which is connected to one end of a lever 26. Levers 24 and 26 are pivotally connected at their midpoints and connected at their other ends to another pair of levers 27 and 28 pivotally connected at their midpoints and connected at their ends to an-

other pair of levers 29 and 30 pivotally connected at their midpoints. Lever 29 has one end connected to a rocker arm 31 mounted for oscillation on a pivot 32 on one of the uprights 12 and lever 30 is connected at one end to part 33a of a scissors arm also pivotally mounted at 32. The scissors arm is made of two parts 33a, 33b secured rigidly together at 34 and at this point, the scissors arm is connected to one end of a spring 35 having its other end anchored on the rail 20, the spring tending to swing the scissors arm in a counterclockwise direction about pivot 32.

A shaft 36 driven by any suitable means is mounted in suitable bearings 37 on a rail 38 extending between uprights 12 below the rail 10 and the shaft is provided with crank 39 having a lengthwise slot in which a pin 40 is adjustably mounted. The pin is connected by a rod 41 to one end of the rocker arm 31 and the rod 41 may be made in two parts connected by a turn buckle 42 so that the length of the rod may be varied as desired.

The part 33b of the scissors arm is formed at its lower end with a slot 43 in which is adjustably mounted a pin 44. On this pin is pivotally mounted one end of a bar 45 formed at the other end with a slot 46 in which is received a pin 47 which may be placed in one or the other of a number of holes spaced along the rocker arm 31.

The movement of the needle carriage in one direction is limited by a stop 48 mounted on rail 10, this stop having a portion extending across the top of the rail and another portion extending down the rear surface of the rail and attached to a bar 49 extending along the rail and movable in guides 50 secured to the rail. A spring 51 is attached to one end of the bar 49 and to a fixed point on the rail. The carriage is formed at its rear end with a plate 52 and, at the limit of the retracted movement of the carriage, the plate 52 engages the stop 48, so that the carriage is brought gently to rest and overrunning is avoided.

In the operation of the needle motion of the construction described, the rocker and scissors arms lie substantially vertical, as shown in Fig. 1, when the needle is in retracted position. As shaft 36 rotates, crank 39 acts through connecting rod 41 to swing the rocker arm 31 in a clockwise direction on its pivot 32 and such movement of the rocker arm causes the levers of the lazy-tongs to swing to expand the system and move the carriage and needle to the left. In such movement of the levers of the system, the scissors arm 33a, 33b is moved clockwise on pivot 32 against the action of spring 35 and the spring tends to take up any slack in the system that may be caused by wear.

When the crank 39 is substantially horizontal and extending to the right (Fig. 2), the lazy-tongs system is fully extended and the needle reaches the end of its travel through the shed. At this time, pin 47 on the rocker arm reaches the end of slot 46 in bar 45, so that further clockwise motion of scissors arm 33a, 33b is prevented. The needle, accordingly, comes to rest without overrunning at a definite point at which the selvage shuttle may pass through the loop of weft thread carried by the needle and lock the inserted shot in place by means of the selvage cord. As the crank moves past the horizontal, the rocker arm 31 begins to swing clockwise to

cause the lazy-tongs lever system to be retracted and, during such movement of rocker arm 31, scissors arm 33a, 33b moves counterclockwise to its initial position, assisted by the action of spring 35. At the end of its retraction, the needle carriage comes into contact with stop 48 and is brought smoothly to rest.

The pin 40 by which crank 39 is connected to connecting rod 41 is adjustable lengthwise of the slot in the crank and the position of the pin determines the speed with which the needle is moved. Adjustment of the length of travel of the needle and also the speed are further effected by adjustment of pin 44 in slot 43 in the portion 33b of the scissors arm and by the location of pin 47 in one or the other of the openings along rocker arm 31.

In the modified construction shown in Fig. 5, the needle carriage 53 is movable along a rail 54 supported on uprights 55 and is connected to a lever 56 at the end of a lazy-tongs system of levers, generally designated 57. The levers 58, 59 at the other end of the system are mounted on a pivot 60 attached to one of the uprights 55 and the ends of levers 58 and 59 are connected to levers 60, 61 which are pivotally connected at their midpoints 62. The pivotal connection between levers 60, 61 is connected by a rod 63 to one end of a lever 64 mounted on a bar 65 extending between rail 54 and a lower rail 66 attached to uprights 55. The other end of lever 64 is connected to a connecting rod 67 which is in turn connected to a pin 68 adjustably mounted in a slot in a crank 69 on a shaft 70 driven in any suitable manner and journaled in bearings on rail 66.

With the Fig. 5 construction, the rotation of shaft 70 causes lever 64 to be swung on its pivot and the lever acts through rod 63 on the lazy-tongs system to cause the system to expand and contract. In the expanding movement of the system, the needle carriage is moved along rail 54 to advance the needle through the shed and when the lazy-tongs system is contracted, the carriage returns to move the needle out of the shed.

I claim:

1. In a loom, the combination of a needle movable into and out of the shed, a lazy-tongs system of levers including an element at one end connected to the needle and a rocker arm and a scissors arm at the other end pivotally mounted on the same pivot, oscillation of the arms in opposite directions about the pivot causing extension and retraction of the system and corresponding movements of the needle, and means for oscillating said arms.

2. In a loom, the combination of a needle movable into and out of the shed, a lazy-tongs system of levers including an element at one end connected to the needle and a rocker arm and a scissors arm at the other end pivotally mounted on the same pivot, oscillation of the arms in opposite directions about the pivot causing extension and retraction of the system and corresponding movements of the needle, a stop limiting the retractile movement of the needle, and means for oscillating said arms.

3. In a loom, the combination of a needle movable into and out of the shed, a lazy-tongs system of levers including an element at one end connected to the needle and a rocker arm and a scissors arm at the other end pivotally mounted on the same pivot, oscillation of the arms in oppo-

site directions about the pivot causing extension and retraction of the system and corresponding movements of the needle, and means for oscillating said arms in opposite directions, including a shaft having a crank and a rod connecting the crank and the rocker arm.

4. In a loom, the combination of a needle movable into and out of the shed, a lazy-tongs system of levers including an element at one end connected to the needle and a rocker arm and a scissors arm at the other end pivotally mounted on the same pivot, oscillation of the arms in opposite directions about the pivot causing extension and retraction of the system and corresponding movements of the needle, means for oscillating the arms in opposite directions on their pivot including a shaft having a crank, and a rod connecting the crank and the rocker arm, a connection between the rocker arm and the scissors arm by which oscillation of the scissors arm in one direction about said pivot is limited, and means acting on the scissors arm to move it in the opposite direction about the pivot.

5. In a loom, the combination of a needle movable into and out of the shed, a lazy-tongs system of levers including an element at one end connected to the needle and a rocker arm and a scissors arm at the other end pivotally mounted on the same pivot, oscillation of the arms in opposite directions about the pivot causing extension and retraction of the system and corresponding movements of the needle, a stop limiting the retractile movement of the needle, a shaft having a crank, a rod connecting the crank to the rocker arm, and a spring acting on the scissors arm and tending to swing it in one direction about its pivot.

6. In a loom, the combination of a needle movable into and out of the shed, a lazy-tongs system of levers including an element at one end connected to the needle and a rocker arm and a scissors arm at the other end pivotally mounted on the same pivot, oscillation of the arms in opposite directions about the pivot causing extension and retraction of the system and corresponding movements of the needle, a stop limiting the retractile movement of the needle, means for oscillating said arms in opposite directions on their pivot, including a shaft having a crank, a rod connecting the crank and rocker arm, and a spring acting on the scissors arm and tending to swing it in one direction on its pivot, and a bar pivoted on one arm and having a slot and pin connection with the other arm, said bar acting to limit the movement of the scissors arm in the other direction on its pivot.

7. In a loom, the combination of a track, a carriage movable along the track on a roller, a nee-

dle secured to the carriage, a lazy-tongs system of levers including an element at one end connected to the carriage and a rocker arm and a scissors arm at the other end pivotally mounted

5 on the same pivot, oscillation of the arms in opposite directions about the pivot causing extension and retraction of the system and corresponding movements of the needle and carriage, means for oscillating said arms, including a shaft 10 having a crank, and a rod connecting the crank to the rocker arm, a bar connected to the scissors arm and to the rocker arm and limiting the movement of the scissors arm in one direction on its pivot, and means acting on the scissors 15 arm and tending to move it in the other direction on its pivot.

8. In a loom, the combination of a track, a carriage movable along the track on a roller, a needle secured to the carriage, a lazy-tongs system 20 of levers including an element at one end connected to the carriage and a rocker arm and a scissors arm at the other end pivotally mounted on the same pivot, oscillation of the arms in opposite directions about the pivot causing extension 25 and retraction of the system and corresponding movements of the needle and carriage, means for oscillating said arms, including a shaft having a crank, and a rod connecting the crank to the rocker arm, a bar pivotally mounted on 30 one arm and connected to the other arm by a slot and pin connection, the bar limiting the movement of the scissors arm in one direction on its pivot, and means acting on the scissors arm and tending to move it in the other direction on 35 its pivot.

9. In a loom, the combination of a track, a carriage movable along the track, a needle attached to the carriage and movable into and out of the shed as the carriage moves back and forth along 40 the track, a lazy-tongs system of levers, including an element at one end connected to the carriage and a rocker arm and a scissors arm at the other end pivotally mounted on the same pivot, oscillation of the arms in opposite directions 45 about the pivot causing extension and retraction of the system and corresponding movements of the carriage and needle, a shaft having a crank, a rod connecting the crank and rocker arm, the shaft acting through the rod to oscillate the rocker arm about its pivot in opposite directions, the scissors arm being swung oppositely to the rocker arm by the action of the rocker arm on the system, by which the movement of the scissors arm in one direction is limited, and a spring 50 acting on and tending to swing it in the opposite direction.

VINCENZO PETRUCCIONE.
